POSTING TRAY FOR LOOSE LEAF BINDERS

Filed Aug. 5, 1927

2 Sheets-Sheet 2

Inventor,
W. H. Browning
Per, Hubert E. Flick
Atty.

UNITED STATES PATENT OFFICE.

WALTER HENRY BROWNING, OF LONDON, ENGLAND.

POSTING TRAY FOR LOOSE-LEAF BINDERS.

Application filed August 5, 1927, Serial No. 210,893, and in Great Britain February 24, 1927.

This invention has relation to improvements connected with posting trays for loose leaf binders.

In mechanical or machine posting systems it is necessary to remove the leaves or sheets from the binder for placing in the typewriter or adding machine and after the required entry has been made to replace them in the binder. Mechanical or machine posting systems, therefore, require the employment of open back binders or binders having detachable covers, one of the covers having locking mechanism integral therewith and the other or both of the covers having posts 15 on which the leaves or sheets are placed.

The invention has for its object to provide for the support of the covers and leaves or sheets prior to and during posting so that they are held against displacement and for 20 their replacement.

The leaves or sheets are preferably of the kind described and claimed in the specification of an application for Letters Patent filed simultaneously herewith Serial No. 25 210,892.

In order that the invention, the object and nature of which have been set forth, may be clearly and readily understood, reference will now be made to the constructional embodiment illustrated on the accompanying drawings, on which:—

Fig. 1 is a perspective view;

Fig. 2 a side elevation with a portion in section; and

35 Figs. 3 and 4 sectional views on the lines 3—3 and 4—4 respectively of Fig. 2.

11 is a base board on which towards one end two superposed plates 12 are mounted. The plates 12 are of different lengths, the 40 upper being the shorter, and are flanged at each end. The plates 12 are so disposed that their flanged ends 13 are spaced apart. Between each pair of flanges 13, the end of an arm or side member of a U-shaped frame 14 is pivotally mounted. 15, 15 are two blocks or members which are mounted on the base board parallel to one another and so as to extend longitudinally of the base board 11 from one end thereof. The blocks 15 have 45 both ends sloping and on the sloping ends adjacent the end of the base board 11 a plate 16 is mounted. This plate 16 is of such length that when mounted in position it extends behind and beyond the arms or side members of the frame 14 to which it constitutes a support. The portions of the plate 50

16 which come directly behind the arms or side members of the frame 14 are cut away, as indicated at 17, to form recesses into which the arms or side members can extend. Between the recesses 17 the plate 16 has on its forward edge an upstanding flange 18, which has at each end an extension or lug 19. The recesses 17 are such that they support the frame 14 at a convenient angle to ensure easy manipulation of the leaves or sheets when posting is in progress. A pin 20, which extends forwardly, is mounted on each or, as shown, on one of the lugs 19. The blocks 15, in addition to carrying the plate 16, constitute carriers for a pair of members 21, each of which consists of a metal rod or bar, preferably of semicylindrical section, bent as shown to somewhat more than a right angle. The members 21 are carried at their one ends by brackets 22, to which they are secured and which are, in turn, mounted on the blocks 15 adjacent the ends to which the flanged plate 16 is secured. The members 21 are of such length and shape that when their one ends are mounted as described, their other ends come above and rest upon the other sloping ends of the blocks 15 in which positions they are held by brackets 23. The members 21 are secured to the brackets 22 and the brackets 22 are mounted on the blocks 15 in such wise that the ends of the members 21 are spaced away from the flange 18, the ends of the brackets 22 coming directly below the flange 18. The construction and arrangement are such that two depressions or recesses 24 are formed directly adjacent to the flange 18. The brackets 23 are shaped at one part to engage the members 21 and at another part are cut away, as shown at 25, to form recesses or seats. 26 is a second U-shaped frame. This frame 26 is placed towards the other end of the base board and is supported in an inclined position by brackets 27 mounted on the base board. The frame 26 is so positioned that the free ends of its arms or side members are in line with the ends of the members 21 that rest on the sloping ends of the blocks 15. As seen in side view the frame 26 with portions of the members 21 form a V.

A, B are the two covers of a loose leaf binder and C are leaves or sheets thereof. The metal 29 of the cover A contains the lock and this metal is provided with one or two holes 28. The holes 28 are of a size and pitch to permit the engagement of the pin

or pins 20 therewith, and are further such that they will permit of movement of the cover A or its metal 29 relatively to the pins 20 and in a downward direction. The metal 33 of the cover B has the posts 30 mounted thereon. 31 is a metal retaining post adapted to be removably mounted between the metals 29, 33 between posts 30. In addition to the hole or holes 28, the metal 29 has other holes to receive the ends of the posts 30, 31. The retaining post 31, when posting is in progress, is placed on a stand or support 32 mounted on the base board 11. When posting is to take place, the loose leaf binder is placed on the stand described with its cover A in contact with the frame 14 and its cover B resting on the members 21 with the pin 20 (or pins) engaging the hole 28 (or holes). The back edge of the cover A is positioned over, and may be partly entered into, the depressions or recesses 24, the back edge of the cover B resting on the members 21 preventing its complete engagement therewith. Displacement 25 of the binder is thus prevented. The lock is now operated to release the cover B and permit of its removal. The cover B when moved away from the cover A and leaves C is placed in contact with the frame 26 with its back edge bearing on the members 21 below the brackets 23 and the posts 30 resting in the recesses 25 of said brackets. The brackets 23 hold the posts 30 in a position in which the leaves can be placed directly 35 thereon when thus seated in the recesses 25. The cover B is thus held against displacement. As the cover B with posts 30 is withdrawn from cover A, the leaves C move downwardly into engagement with the members 21 and are held against lateral displacement by the engagement of the two projections on the edge with the members 21 as shown in Fig. 3. When the cover B is withdrawn, the cover A is released and will 40 also move downwardly until it rests on the bottoms of the recesses or depressions 24. The retaining post 31 is now removed and placed in its holder. Posting can now be undertaken, the leaves C being transferred one or more at a time from the members 21 and placed on the posts 30, any leaf on 45 which it is desired to make an entry being placed in the adding machine or typewriter during its transfer. When all the leaves C have been transferred from the position adjacent cover A to that adjacent cover B, the retaining post 31 is passed through the holes 34 in the leaves C into its seating in the metal 33 of the cover B and the cover A is 50 transferred and locked to cover B.

It will be understood that double-post binders can be employed in which case the

posts on one of the covers will serve the same purpose as the members 21, the posts on each of the covers being suitably supported to 65 carry the leaves and to permit of the reconnection of the covers.

What I claim is:—

1. Means for dealing with the covers and leaves of a loose leaf binder of the post type 70 during machine posting comprising a base board, oppositely inclined cover supports mounted on the base board, angled leaf supports also mounted on the base board and disposed between the cover supports, and brackets to support the posts on one of the covers mounted adjacent one of the cover supports.

2. Means for dealing with the covers and leaves of a loose leaf binder of the post type 80 during machine posting comprising a base board, oppositely inclined cover supports mounted on the base board, angled leaf supports also mounted on the base board and disposed between the cover supports, a plate 85 mounted behind one of the cover supports and carrying means to engage the cover resting thereagainst to prevent its lateral displacement and brackets to support the posts on the other of the covers mounted adjacent the other of the cover supports.

3. Means for dealing with the covers and leaves of a loose leaf binder of the post type 95 during machine posting comprising a base board, oppositely inclined cover supports 95 each consisting of a U-shaped frame mounted on the base board, the one fixedly and the other pivotally, angled leaf supports also mounted on the base board and disposed between the cover supports, a 100 flanged plate mounted behind the pivotally mounted cover support to support the same in its operative position, a pin mounted on said plate to engage a hole in the one of the covers and brackets to support the posts on 105 the other of the covers mounted adjacent the fixed cover support.

4. Means for dealing with the covers and leaves of a loose leaf binder of the post type 110 during machine posting comprising a base board, oppositely inclined cover supports mounted on the base board, angled leaf supports also mounted on the base board and disposed between the cover supports, a plate mounted behind one of the cover supports and carrying means to engage the cover resting thereagainst to prevent its lateral displacement and brackets constituting a 115 means of attachment of the angled leaf supports and a support for the posts on the other of the covers mounted adjacent the other of the cover supports.

Dated this 22nd day of July, 1927.

WALTER HENRY BROWNING.
